CLAIM

The ornamental design for a solar lamp, as shown and described.

DESCRIPTION

FIG. 1 is a top perspective view of a solar lamp, showing my new design;

FIG. 2 is a bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 2;

FIG. 11 is a partial enlarged view of FIG. 3; and,

FIG. 12 is a partial enlarged view of FIG. 5.

The broken lines in the figures illustrate portions of the solar lamp, which form no part of the claimed design.

The dash-dot-dash lines are for annotating enlarged views, which form no part of the claimed design.

1 Claim, 9 Drawing Sheets
